UNITED STATES PATENT OFFICE.

ALONZO R. BOYNTON AND WILLIAM C. LOCKE, OF AUBURN, NEW YORK,
ASSIGNORS TO DRIGGS, MOSHER & CO., OF SAME PLACE.

DEVICE FOR MAKING BUTTON-MAKING MOLDS.

SPECIFICATION forming part of Letters Patent No. 257,464, dated May 9, 1882.

Application filed August 18, 1880. (No model.)

To all whom it may concern:

Be it known that we, ALONZO R. BOYNTON and WILLIAM C. LOCKE, both of Auburn, in the county of Cayuga and State of New York, have invented certain new and useful Improvements in the Art of Making Dies for Forming Buttons of Plastic Material, of which the following is a specification, reference being had to the accompanying drawings, in which—

10 Figure 1 represents in perspective a transfer-plate used with our improvements, said transfer-plate resting upon the bottom die-plate of a mold for making buttons. There is also shown a guide-plug and drilling-bit to assist in giving form to said die-plate. Fig. 2 represents a vertical section of the same through one row of holes, guide-plug, and bit. Fig. 3 is a top view of the bottom die-plate having some of its button-matrices completed and 15 others incomplete. Fig. 4 is a transverse section of the incomplete bottom die-plate, taken between the button-matrices in tapering cavities made to receive surplus material. Fig. 5 is a perspective view of the tool used in forming the rim of the button-matrices. Fig. 6 is a bottom view of the same in perspective. Fig. 7 is a vertical central section of the same.

Our invention relates to the art of making dies for forming buttons of sheets of plastic material, and to the tools for making said dies in a correct and expeditious manner.

Heretofore it has been a slow and expensive operation to prepare a pair of these dies, on account of the extreme care necessary to have 35 the circular edge of each matrix forming the back of a button (on a plate containing perhaps a hundred of them) coincide exactly with the circular edge of each matrix forming the front of a button in the second plate of the 40 pair, to obviate the formation of any fins upon the circular edge of the button.

The object of our invention is to produce molds for making buttons of large or small sheets of plastic material, in which molds the 45 edges of each pair of matrices will exactly coincide all around their circumference, and to produce these molds at a much reduced cost.

Our invention consists in combining with the top or bottom die-plates of a button-mold 50 and a transfer-plate provided with any desired

number of holes, (corresponding with the number of buttons to be molded at a time,) and adapted to be secured to said top and bottom plates, a perforated guide-plug made to fit the holes in the transfer-plate, and a drilling-bit 55 made to fit in the perforation of the guide-plug.

In the drawings, B represents the die-plate to be used (after completion) to mold the bottom of buttons, and C is a plate having a series of regularly spaced perforations, c, used as 60 guides in drilling the plate B. These plates are shown as united by dowel-pins a to retain them immovably together while a series of shallow holes, b, corresponding with the center of the perforations c, are to be drilled therein. 65 To find the center of the comparatively large perforations c, a plug, D, is used. This plug fits the interior of each hole c. It is bored through its center to receive a drilling-bit, E, and its milled head extends enough above the plate C 70 to be readily grasped and the plug transferred from one of the holes c to the other. The stem of the bit E fits the bore in the plug D, and thus the plate B has the shallow holes b drilled therein in the same order as they were first 75 made in the transfer-plate C. After all the shallow holes b have been made in the die-plate B the transfer-plate C is removed. The next operation consists in cutting a circular groove, d, in the face of the die-plate around 80 each one of the holes b, but at such a distance therefrom that the inner edge of said groove will form the rim of the matrix of each button. For this purpose the tool shown in Figs. 5, 6, and 7 is used. It differs from cutter-heads 85 now in use only in details of construction as hereinafter described. It has a flat-pointed spindle, F, having its lower end, f, turned to fit in the shallow holes b of the die-plate and sufficiently hardened not to perceptibly wear 90 while in use. This spindle is placed in the center of a cutter-head, G, provided with a hollow stem, G', the upper part of which is internally screw-threaded to receive and be connected to the hollow spindle G'. The stem G' 95 has an internal shoulder, g, to sustain the spindle F and keep it from dropping out of the cutter-head, the collar f' upon said spindle resting upon the shoulder g when the tool is at rest, the internal spring, h, bearing upon this 100

collar at one end and at the other against the upper end of the cavity in the hollow spindle G^2 . The cutter-head G has two radial grooves in its under face, within which is placed either 5 the stem i of the cutter-tool i' or the holder j of the cutter-tool j' , the latter tool being made of a small piece of round bar-steel secured with the screw j^2 , the stem i or holder j being retained at any desired distance from the center 10 of the cutter-head by screws k passing through slots g' in said cutter-head. After having cut the circular grooves d in the face of the die-plate the transfer or guide plate C is again placed upon said die-plate and retained thereon by the dowel-pin a . A drill having its diameter of the same size as the hole c and provided with preferably four cutting-edges of the form intended for the bottom of the buttons is introduced into each one of the holes 15 c in succession and the previously-made shallow holes b are enlarged, producing the saucer-like cavities or matrices b' , with sharp edges b^2 for giving form to the buttons. The metal between the matrix is then drilled out, producing 20 cavities b^3 to receive the surplus plastic material of the sheets used in forming these buttons when said material is squeezed between the top and bottom die-plates of the mold. 25

By the above-described means we obtain dies for pressing buttons of plastic material 30 having a more correct and uniform shape than heretofore, and at a much reduced cost.

Having now fully described our invention, we claim—

1. As a means to facilitate and improve the 35 making of molds for buttons, a transfer-plate provided with dowel-pins a and a series of holes, c , of a size equal to or larger than the buttons to be molded, in combination with a hollow guide-plug, D , made to fit within the 40 holes c , and a drill, E , in said guide-plug, substantially as and for the purpose described.

2. The combination of the yielding spindle F , having its outer end flat and turned at f to the desired size, and the cutter-head G , having 45 grooves in its under face, with the interchangeable cutters i' and j' , substantially as and for the purposes set forth.

ALONZO R. BOYNTON.
WILLIAM C. LOCKE.
